SUPPLY VALVE MECHANISM

Raymond E. Crane and James M. Hendrickson,
Kittanning, Pa.

Application November 28, 1942, Serial No. 467,238

2 Claims. (Cl. 137—104)

This invention relates to certain improvements in sanitary fixtures and particularly to a novel ballcock or valve assembly for water closet flush tanks.

More specifically, the said invention comprises a unitary housing and support for the valve parts and operating mechanism, said housing being made of readily available materials to the exclusion of metal and so designed and arranged as to reduce to a minimum the problem of assembly and machine work.

At the present time practically all of the ballcock assemblies are made of brass or bronze, comprising an upstanding water supply pipe or conduit secured to the bottom of the flush tank, and threaded on to the upper end of said tube or the like is a metal casting also of bronze or brass, providing a casing for the flush valve mechanism and pivotal support for the yoke usually associated with the rod supporting the float. This casting or housing is machined to provide outlets for discharging the water into the tank and for the vent to the overflow. The casting is further machined to slidably receive therein a metallic piston or plunger valve, which plunger is adapted to cooperate with the valve seat formed in said casting and these cooperative parts require further machining. Associated with the plunger valve member, is a yoke carrying the rod for the float usually provided for operating said valve, said yoke being pivotally supported from the upper end of the casting. Here again these cooperative pivoted parts require machining or a machine fit for efficient and smooth operation.

The object of applicants' invention is to provide a one piece housing for the supply valve mechanism, which is formed of integral parts of earthenware or other plastic and designed to eliminate much of the corrosive metal and machine work ordinarily required when using metal parts.

Another object of the invention is to provide a novel non-metallic valve assembly to be mounted in said housing, whereby the interior of said housing at this point is not required to be accurately formed.

Another object is to design and construct the separate valve assembly so that it can be located and secured in the housing at the proper predetermined point in relation to the pivotal points of its operating means.

A further object is the production of a non-metallic valve assembly unit comprising a cylindrical sleeve or the like, and an accurately fitted piston both made of china, vitreous or plastic material.

A still further object is to so construct the hous-

ing as to permit the mounting of said valve assembly as a unit in said housing to insure its proper functioning with respect to the operating lever of the float valve mechanism.

5 A still further object of the invention is to construct the housing either as a separate unit to be secured within the flush tank, or said housing may be formed as an integral part of the flush tank, both being made of the same non-metallic material and designed to operate in substantially the same manner.

A still further object of the invention is to construct all of said parts, as above enumerated, to wit, the housing, valve mechanism, valve operating mechanism and conduits of non-metallic parts such as china, plastic, and like available non-corrosive and cheap materials.

The preferred embodiment of the invention is illustrated in the accompanying drawings in which:

20 Figure 1 is a side elevational view of the improved and novel non-metallic assembly housing for the tank flushing means;

Figure 2 is a front elevational view;

25 Figure 3 is a vertical transverse sectional view thereof;

Figure 4 is a detail view partly in section of the preferred valve unit used in connection with the assembly housing;

30 Figure 5 is a view in front elevation of the valve unit piston;

Figure 6 is a vertical section view on line 6—6 of Figure 5;

Figure 7 is a top plan view illustrating the invention integrally combined with a water closet flush tank;

Figure 8 is a vertical transverse sectional view of this modified form of the invention on line 8—8 of Figure 7; and

35 40 Figure 9 illustrates the preferred form of valve unit shown in Figure 4 as applied to the integral construction.

Referring to the drawings in detail, and with particular reference to Figures 1, 2 and 3, the 45 improved device comprises a hollow cylindrical member 1, provided with a base 2, a lateral extension 3 and a pair of parallel upstanding ears or flanges 4, all formed as an integral unit of molded plastic or vitreous material.

50 The hollow interior of member 1 comprises a chamber or conduit 5 provided at its lower end with a water inlet opening 6 and the upper end of said chamber is in communication, through a passageway 7, with a valve receiving chamber

55 8. In the form shown in Figure 3, this passage-

way terminates in a valve seat 9 formed integrally therewith.

This valve receiving chamber 8 is also in communication with a water discharge conduit 10 formed in the lateral extension 3, adapted to receive a water discharging "hush tube" 11, preferably of plastic material extending downwardly with its lower end terminating adjacent the base 2 of the member 1. This lateral extension 3 is also constructed with a passageway 12 in communication with the chamber 8, providing a supporting means for the usual vent tube (not shown) running to the overflow of the flush tank in which the above parts are mounted in a manner to be hereinafter fully described.

The base 2 of the member 1 is constructed with a circular recess to receive a threaded nipple 14, said nipple being securely cemented within the recess. This recess is provided with annular anchoring grooves or the like 15 and a gasket 16, whereby a water tight and substantially rigid construction is produced.

This nipple 14 provides the necessary means for securing the member 1 to the bottom of a flush tank 17, in the manner as clearly shown in Figure 3.

As hereinbefore stated, the upper end of the member 1 is provided with an open top chamber 8, which is adapted to receive a valve unit comprising a sleeve or cylinder 18 and a cooperating reciprocating piston 19, said piston having the usual packing rings 20 and the lower end of said piston carries a disc washer or gasket 21 adapted to engage the valve seat 9 when the valve is in its closed position.

The upper end of said piston or plunger 19 is constructed with a vertically disposed web portion 22 and a head or cap 23, for operative cooperation with the valve operating lever to be hereinafter described.

All of these parts of the valve unit just referred to, with the exception of packing are preferably formed of molded plastic material, the same as that forming the housing member 1 as will be hereinafter described in more detail with reference to Figures 4, 5 and 6.

In Figure 3, however, the cylindrical sleeve 18 is illustrated as made of either metal or plastic and cemented in the valve receiving chamber as shown. The piston or plunger 19 may also be made of metal and the valve seat 9 as shown in said Figure 3 is formed as an integral part of the main housing 1.

Furthermore, other types of valves may be used without departing from the main novel features of the instant invention.

However, the preferred construction of valve unit is that illustrated in Figure 4 to be later described.

Again referring to Figure 3, the vertically disposed web 22 of the valve piston 19 is straddled by a bifurcated lever member 24 carrying the rod 25 of the controlling float (not shown).

All of these parts, including the float, may also be made of suitable plastic materials.

The lever 24 is provided with a pivot pin 26, supported in oppositely disposed openings 27 formed in the vertical parallel ears or flanges 4.

It will be noted that the valve receiving chamber 8 is open at the top, making it readily accessible for the mounting of the valve unit, or replacement thereof. Furthermore this chamber 8 is of sufficiently large diameter, with respect to the outside diameter of the sleeve 18 of this valve unit, to permit a sufficient amount of lateral play

in the initial mounting of the unit in position, so that the same can be located in its proper predetermined position with respect to the operating pivot 26 and thereafter securely cemented in place.

Referring now to Figures 4 and 9, the preferred valve unit, comprises a sleeve or cylinder 26' having formed integrally therewith a valve seat 27. Slidably mounted within this cylinder 26' is a piston or plunger 19 and both of these members are formed of molded plastic material. An accurate fit is provided between these parts and said parts as an assembled unit are secured in proper adjusted operative position by cement or the like 15 similar in a manner to that shown in Figure 3.

It will be noted that in this preferred form the valve seat is carried by the cylinder 26' and not formed around the opening 7 of the main body member 1 as in Figure 3, so that a predetermined and proper alignment of these parts will be assured before the assembled unit is inserted in the valve receiving chamber 8 of the cylindrical main body member 1.

A modified form of the invention is illustrated in Figs. 7, 8 and 9, wherein the main body member 1 is molded as an integral part of the flush tank 17, but is otherwise similarly constructed as in Figures 1 to 6, inclusive, with respect to the valve receiving chamber 8 and the passageway 20 to and from said valve chamber. Moreover, this valve receiving chamber is adapted to have mounted therein the same types of valve units as shown in Figures 3 and 4, and the same corresponding reference characters have been used 35 to designate these same parts in Figures 7, 8 and 9.

In order to form this modification with the flush tank as an integral part thereof, certain necessary and simple changes have been made.

Referring to Figure 7, it will be noted that the parts are preferably arranged in one corner of the tank and it was necessary only to provide the main body portion 1 with one upstanding ear or flange 28 to support the pivot pin 26, the other end of said pivot pin being supported by the adjacent wall of the tank 17. In addition, the base of the member 1 is provided with a laterally extending chamber 29 having a connection 30 to the source of water supply through the bottom of the tank.

In each and all forms as shown, the advantages and operation are the same. The rise and fall of the float valve (not shown) controls the operation of the valve piston 19, and correspondingly the supply and discharge water to and from the apparatus through passageways provided in the molded plastic main body member 1 integrally formed as a single unit to house the valve mechanism. This main body member is not only made of plastic material but practically all of the valve working parts carried thereby are preferably made of similar plastic material so that substantially all metal parts have been dispensed with and eliminated and in view of the readily available materials used in this improved device, and the novel manner of construction and design, the applicants have made a valuable and meritorious contribution to the art.

Throughout the specification where reference has been made to "molded plastic material" it is to be understood that this expression is used in the broad sense and is intended to cover any ceramic body produced from plastic material, such as china, glass and similar vitreous materials.

What we claim is:

1. A valve combination for flush tanks and the like, comprising a hollow member provided with a valve receiving chamber and water inlet and outlet passageways communicating with said chamber, a valve unit positioned in said chamber, said unit comprising a one-piece cylinder and valve seat in spaced relation to the walls of said valve receiving chamber, a piston closely fitted within said cylinder for engaging said seat, means for pivotally supporting a valve operating mechanism on said hollow member, and means for securing said valve unit in proper adjusted position relative to the pivotal point of said valve operating mechanism.

2. A fitting for flush tanks and the like, comprising a one-piece tubular member having a valve receiving chamber in its intermediate portion, a water discharge passageway extending

5 outwardly and downwardly from said chamber and in communication therewith, a water venting passageway extending outwardly from said discharge passageway, a valve unit positioned in said valve receiving chamber, said unit comprising a one-piece cylinder and valve seat mounted in spaced relation to the walls of said valve receiving chamber, a piston closely fitted within said cylinder for engaging said seat, means carried by the upper end of said tubular member pivotally supporting a valve operating mechanism, means for securing said valve unit in proper adjusted position relative to the pivotal point of said valve operating mechanism
10 15 and means provided at the lower end of said member for securing the same within a flush tank.
